UNITED STATES PATENT OFFICE

HOWARD TERHUNE, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA

KNOCK-OFF FOR BOARD DROP HAMMERS AND THE LIKE

Application filed May 23, 1929. Serial No. 365,491.

I have invented an improved drop hammer, and, more especially, a drop hammer of the kind designated as board drop hammers.

In a device of this character, the hammer is elevated by means of comprising feed rolls which engage and release a suitable part, so that the hammer can be lifted and dropped in succession. An object of the invention is to reduce friction and wear to a minimum and, at the same time, provide a construction that can be easily repaired when necessary.

Another object of the invention is to provide means for securing the most advantageous operation of the feed rolls and to obviate risk of injury that might ensue from the improper actuation thereof.

A further object of the invention is to provide suitable means for cushioning the so-called front rod, which constitutes the chief means for controlling the movement of the feed rolls into and out of operative position with respect to the ram; the cushioning means acting upon the front rod as the latter falls when the downward movement of the hammer is completed, so that the rod carries the feed rolls easily and safely into position to raise the hammer for its next stroke.

An additional object of the invention is to provide a board drop hammer having parts arranged to enable the steps in the operation of the hammer to be properly timed; so that the power for lifting the hammer can be brought into play at the exact instant required, without waste of energy and loss of motion.

A further object of the invention is the provision in a board drop hammer of a front rod arrangement eliminating, insofar as possible, the destructive hammering between the rod and its several seats which hold it in its raised and lowered position.

A still further object of the invention is the provision of a front rod mounting for hammers of this type which will permit ready adjustment, or movable and substitution, of the stop-engaging element of the rod.

The nature and advantages of the invention are fully set forth in the following description, taken in connection with the drawings,

which show one form in which the invention is embodied. The construction herein disclosed, however, is intended by way of illustration only, and I reserve the right to make changes in the shape, size and relative arrangement of the various members, not necessarily shown herein but nevertheless coming within the principle of the invention and embraced within the scope and meaning of the appended claims.

On the drawings

Fig. 1 is a front view of the board drop hammer according to my invention;

Fig. 2 is a side view of the same;

Fig. 3 is a sectional view on the line 3—3 of Fig. 1; and

Fig. 4 is a front view of the parts shown in Fig. 1.

On the drawings, the same numerals identify the same parts throughout.

I use the numeral 1 to indicate the anvil of a board drop hammer, secured upon a suitable bed or base, between the lower ends of side frames 2; which are in upright position. Upon the tops of these frames is the housing 3 in which are mounted the feed rolls 4. These rolls operate to engage and disengage the board 5; which moves up and down between the rolls 4 and is secured at its lower end to a hammer or ram 6. This ram travels up and down between the side frames 2 and is engaged by suitable vertical guides 7; which may have the form of ribs and are received in grooves in the sides of the hammer 6.

In practice, the rolls 4 are so mounted and operated that when they are moved into contact with opposite faces of the board 5 and rotated, the board is impelled upward to lift the hammer; and when the rolls 4 are moved apart, so that they no longer frictionally engage with the board 5, the hammer can fall, drawing the board 5 down with it. Suitable pulleys are usually employed to turn the rolls 4; and at 8 is indicated the front rod; which extends from a pivotal connection 8—9 a therefor at the top of the housing 3 down along the front of the machine and is so connected at its upper end that, when the rod is lifted, the rolls 4 are caused to disengage the board 5 to permit the hammer to drop; and

when the rod is moved downward, the rolls 4 are caused to move into contact with the board 5 to lift the hammer. The construction thus far described is well-known and forms no part of this invention.

6 Adjacent its lower end, one of the side frames 2 is provided with a couple of bearings 9 in proximity to the front bar 8 and in these bearings is mounted a pin 10 carrying a hardened roller 11. This roller is between the 10 bearings 9 and is free to rotate on the pin 10. When the rod 8 is in its uppermost position, a seat 12 rests upon this roller, this seat being carried by a dog 13 yieldably supported from 15 clamp 14; and yieldably secured thereto, both the dog and the clamp encircling the rod 8. The clamp 14 is made fast on the rod, but the dog 13 can move to some extent on the rod 8. The connection between the 20 dog 13 and clamp 14 comprises headed studs 15 secured to one thereof and slidably directed through the other thereof. Surrounding these studs, between the clamp and dog, are springs 17 which yieldably maintain the 25 dog and clamp in spaced relation. The clamp is illustrated as provided with sockets 16 receiving the upper ends of these springs. The dog 13 can, therefore, move on the rod 8 as far as the springs 17 permit. Of course, 30 the clamp 14 can be loosened and its position on the rod 8 adjusted as desired.

35 Affixed to the rod 8 above the clamp 14 is a knock-off dog 19 having clamping engagement with the rod 8 so that it can be adjusted and secured in desired position. This dog extends towards the path of movement of the hammer 6 which has a cam projection 20. In the downward movement of the ram 6, the cam projection 20 will engage the knock-off 40 dog 19 and push the rod 8 outward from the front of the adjacent side frame 2, causing the seat 12 to clear the roller 11 and enabling the rod to drop.

45 Below the roller 11 is a yoke 21 receiving the lower end of the rod 8 between the arms thereof and carrying a grooved roller 22 mounted upon a removable pin 23. The rod 8 moves between the roller 22 and the bottom of the yoke. In line with the yoke, the adjacent side frame 2 has a channel 24 through which passes the shank 25 of the yoke, the channel being enlarged at its opposite end on the rear of the side frame 2, as shown at 26, to provide a shoulder 27. In the enlarged 50 part 26 of the channel is a spring 28 abutting the shoulder 27 and the adjacent end of the shank 25 is threaded to receive a stop nut 29. When the rod 8 moves away from the adjacent side frame 2 to make the pin 12 clear the roller 11, it can exert a thrust upon the roller 22 and pull the yoke 21 out to some extent 55 against the force of the spring 28.

60 On a suitable shoulder adjacent the roller 11, the side frame 2 adjacent the rod 8 carries 65 a cushioning pad or stop made of several

layers of leather or the like, this pad being held in place by a pin 31; and the seat 12 of the dog 13 when the rod is dropped far enough, will strike this leather cushion and be arrested thereby. At this time, the rod 8 70 may move a little further; the springs 17 yielding to permit the separation of the clamp 14 and the dog 13.

To cause the rod 8 to be lifted, I mount 75 on the rod, adjacent the upper limit of movement of the hammer 6, an arm 33 upon a pivot 34 carried by a clamp 35, which can be adjustably secured to the rod 8. One end of this arm 33 projects across the inner edge 80 of the adjacent side frame; and the opposite end 36, which may be rounded, extends into a recess 37 of a fixed bearing block 38. The hammer 6 has a projection or stud 39 to engage the lower side of the arm 33 and lift it. The block 38 is secured in the adjacent side 85 frame 2 by bolts 40 and suitable means may be provided for enabling this block to be raised or lowered and secured by the bolts 40 in adjusted position.

The machine is also provided with a treadle 41 at the front below the anvil 1; the treadle being mounted on a shaft 42 which carries an arm 43, attached to a link 44 which runs up to the top of the machine and is there connected to one or more suitable arms 90 indicated at 45 to which control clamps, not shown, normally acting to engage the board 5 and keep the board in its elevated position. Whenever the treadle 41 is depressed, these 95 clamps are withdrawn and the board 5 released for regular operation. Such clamps are well-known to those acquainted with this art and need not be further illustrated or further described herein.

100 In operation, whenever the hammer is to be used, the treadle 41 must be first depressed to release the board 5. Then, if the hammer has been lifted high enough for the projection 39 to move up the arm 33, thus lifting the rod 8 to disengage the rolls 4 from the board 5, the hammer 6 at once drops. At this time, the rod occupies the position shown particularly in Fig. 3. When the hammer reaches the end of its downward movement, the cam projection 20 engages the knock-off 105 dog 19 and pushes the rod away from the adjacent side frame 2 so as to move the seat 12 out of alignment with the frictionless rest or support afforded by the roller 11, the yoke 21 then being drawn out against the force 110 of the spring 28. The rod now drops until the seat 12 of the dog 13 is arrested by the cushion stop 30 and this downward movement of the rod causes the rolls 4 to make contact 115 again with the opposite faces of the board 5 to lift the hammer. The raising and dropping of hammer thus takes place so long as the treadle 41 is depressed and can be stopped 120 by releasing pedal 41.

125 By this design of the drop hammer, fric- 130

tion and wear are minimized, while any necessary repairs are rendered easy to make. The friction is greatly lessened by the anti-frictional rollers 11 and 22.

5 As the rod reaches the lower limit of its movement, it does not stop abruptly, because of the effect provided by the pad 30 and the spring 17. This cushioning of the fall of the rod 8 causes the rolls to engage the opposite faces of the board 5 gradually instead of with an impact or blow. If the rolls 4 were permitted to engage the board 5 with a pronounced impact, the board 5 would soon be destroyed, first by the direct effect of the 10 blow and next because the blow or impact would cause the rolls to rebound from the board 5 and slip, thus grinding or scoring the two faces of the board.

15 A further advantage of the construction above described resides in the fact that the knock-off or outward movement of the rod 8 to enable the seat 12 to slip past the roller 11 can be timed so that the rolls 4 will again engage with the board 5 at the instant the 20 hammer strikes the anvil 1 and rebounds. This enables the hammer to be lifted with a minimum expenditure of power, because the inertia of the hammer 6 does not have to be first overcome. The initial upward impulse 25 is provided by the rebound of the ram or hammer and the rolls 4 merely continue the elevation of the hammer 6 thus commenced. If this timing were different, the hammer would have to be started upward from a state 30 of rest and more power to lift the hammer at the end of each working stroke would be needed. The hammer is thus not only efficiently controlled, but is also quite economical and capable of a much longer period of 35 service.

40 Attention is directed to the fact that when the dog 13 is in its lowered position the side face thereof engages against the roller 11 and is held thereagainst by the action of the spring associated with yoke 21. Thus, frictional resistance to movement of the rod upwardly is reduced.

45 Attention is further directed to the fact that the roller 11 provides an effective upwardly and inwardly inclined surface, in advance of the seat proper, against which the lower edge of the dog may engage and over which this edge may ride permitting the dog to come smoothly to its seat. In the ordinary construction where abrupt faces are provided for the seat and dog associated therewith, it is necessary that the rod be elevated sufficiently to provide clearance between these faces, which means that the dog must be elevated above its seat, with the result that the dog slams downwardly on the seat and these two surfaces become rapidly worn, requiring constant adjustment and soon being destroyed. In the present construction it is 55 not necessary that the upward movement of

the rod carry the dog to the upper level of the surface of the seat for with the provision of the cam face included in the roller 11, spring 27 operating through the yoke 21 upon the rod will force the rod inwardly thus 70 wedging it upwardly until it properly engages the seat. This has a further advantage in that slamming of the rod proper against associated portions of the mechanism is eliminated insofar as this is possible.

75 Of course the roller 11 and seat 12 might be reversed, as the same results might be secured if the roller 11 were attached to the rod and the seat 12 on the side frame 2.

80 As a safety measure, the treadle 41 is preferably so connected to shaft 42 that it may be swung upwardly thereabout from its operative position illustrated in solid lines in Fig. 2 to a dotted position as illustrated in this figure thereby placing it in such a position that it is impossible for the operator to accidentally initiate operation of the hammer.

85 I claim:

1. A board hammer comprising a ram to be lifted and dropped, a front rod to control the ram, means for enabling the rod to be raised and lowered according to the position of the ram, a stop for the rod when lowered, a support for the rod when raised, and yieldable means mounted on the rod to engage the stop when the rod is adjacent the end of its downward movement, and the support when the rod is raised.

90 2. A board hammer comprising a ram to be lifted and dropped, a front rod to control the ram, means for enabling the front rod to be raised and lowered according to the movement of the ram, an anti-friction roller mounted in stationary position, and an element carried by the rod to rest upon said roller when the rod is in raised position and engage against the roller as the rod is raised and lowered.

95 3. A board hammer comprising a ram to be lifted and dropped, a front rod to control the movement of the ram, means for enabling the rod to be raised and lowered according to the position of the ram, a stop adjacent said rod, a clamp on said rod, a dog on the rod yieldably secured to the clamp to engage the stop when the rod is in its lowered position.

100 4. A board hammer comprising a ram to be lifted and dropped, a front rod to be raised and lowered to control the ram, means for enabling the rod to rise and fall according to the position of the ram, a clamp fixed to said rod, a dog on said rod, bolts carrying springs for yieldably connecting the dog and clamp together, and a fixed stop to be engaged by the dog when the rod is adjacent its low- 105 ermost position.

110 5. A board hammer comprising a ram to be lifted and dropped, a front rod to control 115

the movement of the ram, means for moving said rod according to the position of the ram, a frictionless rest for said rod when the rod is in its uppermost position, a dog, 5 a clamp secured to the rod and yieldably secured to the dog, and a seat attached to the dog to engage said rest.

6. A board hammer comprising a ram to be lifted and dropped, a front rod to control the ram, means for shifting said rod according to the position of the ram, a roller mounted in stationary position adjacent the rod, a clamp fixed to the rod, a dog yieldably connected to the clamp, a seat carried by the dog 10 to rest upon said roller, arresting means to be engaged by the seat when the rod is shifted to disengage the seat from the roller to liberate the rod for movement, a yieldably mounted yoke, and a roller in said yoke to engage the rod and tending to hold the rod to 15 keep said seat in line with said anti-friction roller.

7. A board hammer comprising a ram to be lifted and dropped, a front rod, means for causing said rod to rise and fall according to the position of the ram, an anti-frictional support, an element mounted on said rod to engage the support when the rod is in raised position, and means constantly urging the rod 20 toward the support, the support having an upwardly and inwardly inclined face at the junction of its upper and its rod confronting sides.

8. A board hammer comprising a ram to be lifted and dropped, a front rod, means for causing said rod to rise and fall according to the position of the ram, and anti-frictional support, and an element mounted on said rod to engage the support when the rod is 25 in raised position, said element being yieldably mounted upon the rod.

9. A board hammer comprising a ram to be lifted and dropped, a front rod to control the ram, means for enabling the rod to be raised and lowered according to the position of the ram, a stop, a support vertically placed 30 above the stop and yieldable means mounted on the rod to alternately engage the support and stop, the support having an upwardly and inwardly inclined face at the junction of its rod confronting and upper faces for co-action with said yieldable means.

10. A board hammer comprising a ram to be lifted and dropped, a front rod to control the ram, means for enabling the front rod to be raised and lowered according to the movement of the ram, an anti-friction roller mounted in stationary position, an element carried by the rod to rest on said roller when the rod is in raised position, and means constantly urging the rod towards said roller to maintain said element against the roller as the rod is raised and lowered.

11. A board hammer comprising a ram to be lifted and dropped, a front rod to control

the ram, means for enabling the rod to be raised and lowered according to the position of the ram, a stop for the rod, yieldable means mounted on the rod to engage the stop when the rod is adjacent the end of its downward movement, an anti-friction roller above the stop with which said yieldable means engages when the front rod is being raised and upon which the yieldable member seats when the rod is completely raised and means constantly urging the rod toward said roller. 70

12. A board drop hammer comprising a ram to be lifted and dropped, a front rod to control the movement of the ram, means for enabling the rod to be raised and lowered 80 according to the position of the ram, a stop, a support spaced from the stop, a yieldable member to alternately engage the stop and support and means adjustably and removably connecting said yieldable member to the 85 rod.

13. A board drop hammer comprising a ram to be lifted and dropped, a front rod to control the movement of the ram, means for shifting the rod according to the position of 90 the ram, a support for the rod when in its uppermost position having vertical and horizontal faces, a roller disposed at the junction of the faces and projecting beyond each thereof, a member secured to the rod seating upon said roller when the rod is raised and means holding said member in engagement with the roller as the rod is lowered. 95

14. A board drop hammer comprising a ram to be lifted and dropped, a front rod, 100 means for causing said rod to raise operated by the ram, a support for the rod, a member on the rod adapted to engage the support when the rod is raised to maintain the rod in raised position, the first-named means 105 elevating the rod through a distance insufficient to cause supporting engagement of said member and means including an inclined face on one of said support and member for further elevating the rod to cause the member 110 to come into supporting engagement with said support, the member being yieldably mounted on the rod.

15. A board drop hammer comprising a ram to be lifted and dropped, a front rod, means for causing said rod to raise operated by the ram, a support for the rod, a member on the rod adapted to engage the support when the rod is raised to maintain the rod in raised position, the first-named means 115 elevating the rod through a distance insufficient to cause supporting engagement of said member and means including a roller on one of said support and member for further elevating the rod to cause the member to come 120 into supporting engagement with said support, the member being yieldably mounted on the rod. 125

HOWARD TERHUNE.
